UNITED STATES PATENT OFFICE.

LOUIS HERZOG, OF BEACON, NEW YORK, ASSIGNOR TO GLENHAM EMBROIDERY COMPANY, A CORPORATION OF NEW YORK.

JACQUARD.

1,214,918.

Specification of Letters Patent.

Patented Feb. 6, 1917.

Application filed June 9, 1915. Serial No. 33,010.

To all whom it may concern:

Be it known that I, LOUIS HERZOG, a citizen of Switzerland, and a resident of Beacon, in the county of Dutchess and State of New York, United States of America, have invented certain new and useful Improvements in Jacquards, of which the following is a specification.

My invention relates to improvements in jacquards and more particularly to jacquards for operating embroidering machines. In jacquards of this class there are provided devices for producing movements of different extents, and these are coupled at each stitch operation with various devices for operating the tambour frame of the embroidering machine, and these latter devices serve to combine the movements of different extents and to translate them into movements of different directions so that many combinations may be obtained.

Since all the tambour frame moving devices are not always connected with the movement producing devices it is customary to lock the tambour frame moving devices at all times except when they are selected for operation, to prevent displacement of the parts and to prevent erroneous results. This necessitates the unlocking of the selected devices so that they may be operated, and my present invention relates to the means for controlling or causing these unlocking operations.

In U. S. Patent No. 528,632, there is shown and described a complete jacquard of the type referred to, and since I have adapted my invention to a jacquard of that type it will simplify this case to make cross reference to that patent; but it is to be distinctly understood that the present invention is not limited to a jacquard of that type only, as it may be otherwise applied.

The object of my invention is to avoid wear on the needle slides caused by the unlocking device, so as to prolong the life of these slides and to avoid erroneous operation of the parts as might happen where the continual friction of the unlocking device on the slides wears the latter away to such an extent as to cause the unlocking device to engage and be controlled by the wrong slide and thus unlock the wrong tambour frame moving devices.

Another object of my invention is not only to avoid wear on these slides by trans-

ferring the action to other parts, or by eliminating the friction to a considerable extent but also to control the unlocking devices from a different part of the mechanism than heretofore in order that the unlocking operations will inerrantly agree with the coupling operations.

In the drawings forming part of this application,

Figure 1 is a longitudinal sectional view through the jacquard, showing the principal parts thereof,

Fig. 2 is a perspective view, on a larger scale, showing the application of my invention to the type of jacquard referred to,

Fig. 3 is a plan view thereof,

Fig. 4 is a vertical sectional view, showing unlocking devices,

Fig. 5 is a plan view of the parts shown in the upper portion of Fig. 4,

Fig. 6 is a horizontal sectional view, showing in plan the parts shown in the lower portion of Fig. 4,

Fig. 7 is an end elevation of the parts shown in Fig. 4, and

Fig. 8 is a perspective view of the links which carry the locking members.

I have shown only such parts of the complete jacquard as are necessary to an understanding of my invention. As above stated, I have shown a jacquard of the kind set forth in U. S. Patent 528,632, by way of illustration.

The shaft 1 is the main shaft of the jacquard, and there are secured thereon the cams 2 and 3. There is a lever rocking on a shaft 7, journaled in bearings 8, one arm 6, of which lever has a roller 5 bearing on the cam 2, whereby this lever will be periodically rocked in accordance with the revolutions of the main shaft.

The other arm 10, of this lever has links 13 fulcrumed thereto one in each of the holes 11. It is to be understood that these links are arranged side by side, and each with an end fulcrumed to the arm 10 in a hole 11, the same as in said patent. Since these links are fulcrumed at different distances from the axis of the arm 10, i. e., at different distances from the shaft 7, they will be reciprocated different extents when the lever is rocked, and the parts operated by these links will also be operated different distances.

Each link 13 is fulcrumed at one end to a vertical slide 14 by a bolt 15. The construc-

tion shown in said patent comprises seven vertical slides lettered G^1 , G^2 , G^3 , G^4 , G^5 , G^6 , G^7 , and there may be seven such slides 14 in the present structure, all arranged to travel parallel to each other between the guides 16 on the base 9, and at their upper edges they are guided in the grooves in the top plate (not shown).

The rocking of the lever arm 10 as indicated in dotted lines, operates through the links 13 to reciprocate all seven slides 14, but each one to a different extent, according to the points at which the links are fulcrumed to the arm 10.

15 The mechanism for moving the tambour frame of the embroidering machine includes four slides 99, which are here shown horizontally disposed in parallel relation the same as in said patent, and they are preferably supported and guided by the same means as the slides L , L^1 , L^2 , L^3 in said patent, with which they correspond. From these slides 99 to the tambour frame of the embroidering machine the same mechanisms 20 may be employed as in the said patent and, since they require no modification they are not shown herein.

These slides 99 operate the movement combining devices and they are coupled to 30 and uncoupled from the slides 14, in order that they may receive motion from the latter in accordance with the control of the jacquard card. These slides 99 require to be locked except when they are being moved 35 by the slides 14, in order that they shall not be displaced and permit erroneous positioning of the tambour frame; and the present invention has to do with the mechanism for controlling the locking and unlocking of 40 these slides or equivalent devices.

The coupling of the slides 14 and 99 in various combinations is controlled from the jacquard card and this may be accomplished 45 through the same mechanism as that shown in said patent, an example of which is herein shown.

The cylinder 65 is the card cylinder, corresponding to the part E^2 in said patent. The jacquard card travels around this cylinder, the latter being rotated step by step. This cylinder is carried upon arms 70 of levers which fulcrum on a shaft 68, the other arm, 71, of which levers is fulcrumed at 73 to a link 72, which is connected and operated by the means shown in said patent. At each rocking movement of the lever 71-70, the cylinder and card are moved toward and from the needles 64 and at each retraction the cylinder is turned sufficiently 60 to bring a new row of perforations in line with the needles.

There is only one needle 64 showing in the present drawings, the others lying behind it. The number and their arrangement are fully shown and described in said patent. In that

structure there are 28 such needles arranged in four groups with seven needles in each group and the same arrangement may be here employed. The number of groups corresponds with the number of slides 99, while the number of needles in each group corresponds with the number of slides 14. For simplicity, only one set of controlling elements will be traced, since the others are merely duplications thereof, in so far as the present invention is concerned.

The needles 64 are slidable toward and from the cylinder in grooves 64^a, in the supports 63. The needle slides 62, one for each needle 64, also slide in the grooves 64^a. The needle has an angular end 66, which engages one of the supports 63 to limit its movement in one direction and this end is engaged by the downward extension 67 of the slide 62, so that rearward movement of the needle 85 will cause a similar movement of the needle slide.

The needle slide has notches 74 and 75 with which the locking pawl 76 engages, like the notches o , o' and pawl O in said patent. The pawl 76 engages in the notches 74 of those slides which are displaced by the card and in the notches 75 of those which are not displaced, in order to hold all the slides against accidental displacement during their 95 active periods. The pawl 76 is connected to the shaft 77 on which is fixed an arm 78 which is rocked through the link 79, as in said patent.

In the present construction the notches o^2 100 of said patent, and the parts co-operating therewith may be omitted because the unlocking action is here otherwise controlled.

Each needle slide 62 is connected by a link rod 60 having a projection 61 projecting 105 therein, with a selector slide 44. The latter is adapted to rock on its curved end and also to slide in grooves in the supports 45, the same as the slides j in the patent.

For each selector slide 44 there is a coupling slide 24, comprising a horizontal portion A and a vertical portion B, which slides move horizontally as well as vertically in the grooves in the supporting rails 25 (four of the latter being shown in the drawings).

The selector slide 44 lies between the blocks 46 on the coupling slide 24, so that the former may reciprocate in relation to slide 24, but the latter will be lifted when slide 44 is rocked.

The end of the slide 44 has a lower notch 47 and an upper notch 48, which lie in advance of each other. The jaw 49 is adapted to engage in the notch 47 or with the solid portion near it, according to whether the slide is selected and advanced or whether it remains in the position shown. In similar manner the jaw 50 engages with the top edge of the slide 44 or in the notch 48, according to whether or not the slide is ad- 100

vanced. When these jaws are closed, the slides which have been advanced will be locked in the lower position and those which have not been advanced will be raised to the dotted line position and will control the coupling devices. The jaw 49 is fixed on a shaft 51, having an arm 53 thereon, and the jaw 50 is fixed on a shaft 52 having an arm 53; and both shafts are rocked by a forked link 55 connected to the arms. The lower end of the link is fulcrumed at 57 to a lever 56. The other arm of the lever 56 has a roller 59 which engages the cam 3 on the main shaft.

There is a pawl 33 arranged to engage in the notches 31 of those slides 24 which are raised and in the notches 32 of those which are not raised, and it serves to hold the slides in either position during their active period. The pawl 33 is fixed to the shaft 34, which latter has an arm 37. To the latter is fulcrumed a link 39 which is also fulcrumed to a lever 41. The other arm of this lever has a roller 43 which engages the cam 3 on the main shaft.

On the horizontal portion A of each coupling slide 24 there is a sliding block 23 which travels along the slide and from which depends a bracket 22. Each block carries a depending coupling rod 18, and in order that four rods 18 may be associated with each slide 14 the rods 18 of four adjacent coupling slides 24 are brought into line and pass through apertures in the slide 14.

Thus, there are four coupling rods for each slide 14, corresponding with the number of slides 99 which may be coupled with the slides 14. There are, therefore, 28 rods 18, controlled by the 28 needles 64. The grouping of the slides 24 is somewhat different than the grouping of the needles, due to the crossing of the link connections 60 in the manner shown in said patent, so that, instead of four groups of seven each, as with the needles, the slides 24 are arranged in seven groups of four each. This arrangement is not imperative to the use of my improvements, but it is thus described merely to illustrate a structure like the said patent as an example.

The several rods 18 are of different lengths and at the lower end each is connected with and adapted to raise a longitudinal bar 19 which is movable vertically but not horizontally in grooves in the brackets 20 carried upon the slides 14. The slides 99 each have forwardly projecting bars 98 lying just above the bars 19, and these have recesses 100 on their under sides to receive the projections 101 on the bars 19. When a bar 19 is lifted by a rod 18 its projection 101 will enter a corresponding recess 100 and thus couple a slide 14 and a slide 99, so that the latter will move with the former when it is reciprocated by the lever 6-10.

The mechanism thus far described corresponds with that of said patent.

The tops of the vertical portions B of the coupling slides 24 are curved at 24' somewhat in the shape of an S, but the curves 70 are alternated; that is, the curve on two adjacent slides is directed forward and on the next two adjacent slides it is directed rearward, as shown in Fig. 2; this arrangement extending to all the slides 24. 75

In the side plates 35 of the jacquard there are arranged the four shafts 83, 84 and 85, 86, disposed in upper and lower planes. These several shafts have flat portions Y to which are attached by means of screws 82 80 the four plates 27, 28, 29, 30, which latter correspond in number with the slides 99.

These plates, 27 to 30, have projections 27', 28', 29', 30', which have contact with the slides 24 and, owing to the curve 24' this 85 contact is a rocking one and therefore there will be very slight friction and wear. The projections 27' on the plate 27 extend forward and there is one projection for the first slide 24 in each of the seven groups. 90 The projections 27' on plate 27, therefore, are adapted to be acted upon by any slide 24, which controls a rod 18 which is adapted to couple any slide 14 with a particular slide 99. 95

The projections 28' on the plate 28 are on a lower plane to those on plate 27 and to correspond with this the slides 24 which operate on the plate 28 are somewhat shorter than those which operate on 27. The projections 28' on plate 28 (seven in number), are acted upon by the slides 24 adjacent those acting on plate 27 and they comprise all the slides which control the coupling of any of the slides 14 with a particular slide 99. 105

The plate 29 has projections 29' extending in the opposite direction to those on plates 27 and 28 and these are acted upon by the slide 24 in each group adjacent those which act on plate 28. Thus, plate 29 is actuated by any of the slides 24 which control the coupling of a certain slide 99. The plate 30, on a lower plane to 29, has projections 30' which are acted upon by the remaining slides 24, corresponding with the 115 remaining slide 99.

On each shaft 83, 84, 85, 86, there is secured a lever arm 89, two of which project forward and two rearward. Each of these lever arms supports a plate 91 through the 120 connecting link 90. These several plates 91 are movable vertically in grooves in the supports 25 and are shown as arranged in line with each other and with the portions B of the slides 24. The plates 91 are of different 125 lengths, so that their lower ends terminate according to the positions of the different bars 98 of the slides 99; and the plates are preferably provided with recesses 31, 32, corresponding with similar recesses in the slides 130

24, so that these plates will be locked periodically in their upper or lower positions by the pawl 33.

In the side plate of the jacquard there are arranged the four studs 95, one above the other, and on these are fulcrumed the lever arms 94. Each lever arm 94 has a roller 92 on its end, which engages in a recess 92' in one of the plates 91. On each bar 98 of a sliding frame 99 there is an engaging member, here shown as a block 97, and on the lever arms 94 there are engaging members 96 which engage the blocks 97.

Operation: When the parts are in the positions shown in Fig. 1, each of the slides 99 is locked against displacement by the block 96 lying in front of the block 97 and the slides cannot be moved until they are unlocked. They will only be unlocked if they are selected for coupling to the slides 14 and if they are not so selected they will remain in locked position. If, therefore, the needle 64 shown in the drawing strikes a solid or unperforated portion of the jacquard card when the cylinder is reciprocated, this needle, and its slide 62, will be moved back, and this will move the slide 44 with which it is connected. When the jaws 49—50 close, this particular slide 44 will be clamped in its original or lower horizontal position and no selection of a coupling element will be effected by it. Neither will it operate any of the unlocking devices.

But should this needle 64 be in line with a perforation in the card it will not be moved back, and neither will the slide 44. When the jaws 49, 50 close, the slide 44 will be swung up to the dotted line position, it being understood that the pawl 33 is disengaged from the notches at this particular moment. The slide 24, engaging the blocks 46 will lift one of the coupling rods 18, and this will raise a bar 19 to carry a projection 101 into a recess 100; and thus one of the slides 99 will be coupled with one of the slides 14, to be moved one stroke forward and back with the latter. The slide 24 when it moves upwardly in this selecting or coupling operation, will engage one of the projections on the plate 27 and it will rock the shaft 83. This will lift one of the plates 91, rock one of the levers 94 and carry its block 96 out of the path of the block 97 on the corresponding slide 99. This latter slide, is, therefore, unlocked, and it is also coupled with one of the slides 14 for movement therewith. The same shaft 83 and the unlocking parts will be operated whether only one or several corresponding slides of the different groups is or are operated. There are twenty-eight slides 24 controlling the coupling, but there are only four slides 99 to be unlocked, so that seven slides 24 are adapted to operate each lever 94.

If any other slide 24 of another group, or

if several of another or other groups operate a coupling device they will also operate their respective unlocking devices.

When the slides 14 and any slides 99 which have been coupled thereto, have made their stroke forwardly and back, the slides 24 and the coupling devices connected therewith will be returned to their starting or initial positions and the lowering of the slides 24 will also permit the plates 27—30 to rock back to their initial positions; and thus the blocks 96 which were unlocked, are returned to locked position, ready for the succeeding operation. In order to properly insure the return of the locking devices I have shown springs 102 having one end connected with a hook 103 on each of the plates 91, and the other end connected with hooks 104 on one of the supports 25; so that the springs pull down the plates 91.

From the above it will be seen that the locking device causes no wear on the needle slides 62 as it may be entirely independent thereof. There will be no appreciable wear on the slides 24 where they strike the projections of the plates 27—30 and it will be unimportant because any slight wear will not cause an erroneous operation of the parts.

Furthermore, it is obvious that if any slide 99 is coupled with a slide 14 it will certainly be unlocked.

In describing the invention in connection with this form of jacquard I do not intend to be understood as limiting the same to this particular embodiment. I have referred to the numbers of parts in certain relations only by way of showing how the invention might be embodied in a machine having the parts as shown in said patent and it is to be understood that the numbers may differ in different structures.

Having described my invention, what I claim is:

1. In an embroidering machine jacquard, the combination of tambour frame moving devices, operating devices for operating them, coupling devices for coupling the operating devices and the tambour frame moving devices, jacquard card actuated members for selecting the coupling devices, and means for locking said tambour frame moving devices and adapted to be operated by said coupling devices independently of said jacquard card actuated members to unlock the tambour frame moving devices.

2. In an embroidering machine jacquard the combination of tambour frame moving devices, operating devices for operating them, coupling devices for coupling the operating devices and the tambour frame moving devices, jacquard card actuated members for selecting the coupling devices, and means for locking said tambour frame moving devices and adapted to be actuated by

said coupling devices independently of said jacquard card actuated members to unlock the tambour frame moving devices.

3. In an embroidering machine jacquard, 5 the combination of tambour frame moving devices, operating devices therefor, coupling devices for coupling the operating devices and the tambour frame moving devices, jacquard card actuated members for selecting the coupling devices, and a plurality of 10 means for locking said tambour frame moving devices, each of said locking means being actuated by any one of a plurality of the coupling devices to unlock the tambour 15 frame moving devices.

4. In an embroidering machine jacquard the combination of tambour frame moving devices, operating devices for operating them, coupling devices for coupling the operating devices and the tambour frame moving devices, and means for locking said tambour frame moving devices and having a 20 rocking engagement with said coupling devices whereby the latter will actuate the locking devices to unlock the tambour frame 25 moving devices.

5. In an embroidering machine jacquard the combination of tambour frame moving devices, operating devices therefor, coupling 30 devices for coupling the operating devices and the tambour frame moving devices, means for locking said tambour frame moving devices, means for operating to unlock said locking devices to permit the tambour 35 frame moving devices to operate, and means for locking said unlocking devices during the operation of the tambour frame moving devices.

6. In an embroidering machine jacquard 40 the combination of tambour frame moving devices, operating means therefor, coupling devices for coupling the operating means and the tambour frame moving devices, means for locking said tambour frame moving devices and means for unlocking said locking devices, and means for locking said 45 unlocking devices in locked and unlocked positions, during the operation of the tambour frame moving devices.

50 7. In an embroidering machine jacquard the combination of tambour frame moving devices, operating means therefor, coupling devices for coupling the operating means and the tambour frame moving devices, 55 means for locking said tambour frame moving devices and adapted to be actuated by the coupling devices to unlock said locking devices, and means for locking said unlocking devices in locked and unlocked positions 60 during the operation of the tambour frame moving devices.

8. In an embroidering machine jacquard the combination of tambour frame moving devices, operating means therefor, rising 65 and falling coupling devices for coupling

the operating means and tambour frame moving devices, means for locking the tambour frame moving devices, said locking devices having a rocking engagement with said coupling devices, whereby the actuation of 70 a coupling device will unlock a locking device.

9. In an embroidering machine jacquard the combination of tambour frame moving devices, operating means therefor, coupling 75 devices for coupling the operating means and tambour frame moving devices, jacquard card actuated members for selecting the coupling devices, devices for locking said tambour frame moving devices independently 80 of said jacquard card actuated members, actuated by a coupling device upon the coupling operation of the latter to unlock a tambour frame moving device and actuated to lock a tambour frame moving 85 device upon the uncoupling operation of a coupling device.

10. In an embroidering machine jacquard the combination of tambour frame moving devices, operating means therefor, devices 85 for coupling the operating means and tambour frame moving devices, including reciprocating members having curved engaging surfaces, devices for locking and unlocking said tambour frame moving devices and including rocking members engaging said 95 curved surfaces whereby they will be actuated by the coupling devices.

11. In an embroidering machine jacquard the combination of tambour frame moving 100 devices, operating means therefor, devices for coupling the operating means and tambour frame moving devices, jacquard card actuated members for selecting the coupling devices, said coupling devices including reciprocating members having engaging surfaces in different planes, devices for locking and unlocking the tambour frame moving 105 devices and actuated independently of said jacquard card actuated members and engaging said engaging surfaces in different planes.

12. In an embroidering machine jacquard the combination of tambour frame moving devices, operating means therefor, devices 110 for coupling the operating means and tambour frame moving devices, devices for locking and unlocking the tambour frame moving devices, arranged to be positively moved into unlocked position by said coupling devices and resistible means for moving them 115 into locked position.

13. In an embroidering machine jacquard the combination of tambour frame moving 120 devices, operating means therefor, devices for coupling the operating means and tambour frame moving devices, jacquard card operated members for selecting the coupling devices, devices for locking and unlocking 125 devices, devices for locking and unlocking the tambour frame moving devices actuated 130

independently of said jacquard card actuated members, said locking devices being in constant engagement with the coupling devices to be actuated thereby.

5 14. In an embroidering machine jacquard the combination of tambour frame moving devices, operating means therefor, devices for coupling the operating means and the tambour frame moving devices, arranged in

10 groups corresponding with the tambour frame moving devices, devices for locking and unlocking the tambour frame moving devices, each locking device being arranged to be actuated by similar coupling devices in

15 the several groups.

16. In an embroidering machine jacquard the combination of tambour frame moving devices, operating means therefor, devices for coupling the operating means and the

20 tambour frame moving devices, said coupling devices being arranged in groups corresponding with the tambour frame moving devices and having engaging surfaces arranged in different planes, devices for locking and unlocking the tambour frame moving devices and having a rocking contact with said engaging surfaces.

17. In an embroidering machine jacquard the combination of tambour frame moving devices, operating means therefor, devices for coupling the tambour frame moving devices and operating means, jacquard card operated members for selecting said coupling devices, and devices for locking and unlocking the tambour frame moving devices, operating simultaneously with said coupling devices and independently of said jacquard card operated members.

18. In an embroidering machine jacquard the combination of tambour frame moving devices and operating means therefor, coupling devices therefor, including coupling slides, locking devices for the tambour frame moving devices, including slides and shafts provided with members having a rocking contact with said coupling slides.

19. In an embroidering machine jacquard the combination of tambour frame moving devices and operating means, coupling devices therefor, including coupling slides, locking devices for the tambour frame moving devices, including slides and shafts provided with members having a rocking contact with said coupling slides.

20. In an embroidering machine jacquard the combination of tambour frame moving devices and operating means therefor, coupling devices therefor, including coupling slides having curved ends terminating in different planes, locking devices for the tambour frame moving devices, including slides and shafts for lifting said latter slides and provided with members having a constant rocking contact with the curved ends of the coupling slides.

21. In an embroidering machine jacquard the combination of tambour frame moving devices and operating means therefor, coupling devices therefor, including coupling slides having curved ends terminating in different horizontal and vertical planes, locking devices for the tambour frame moving devices, including shafts arranged in different horizontal and vertical planes and provided with members having a rocking contact with said ends of the coupling slides.

Signed at New York in the county of New York and State of New York, this 29th day of May, 1915.

LOUIS HERZOG.
